Primary Examiner — Kevin Rudzinski*Assistant Examiner* — Sean D Lough(74) *Attorney, Agent, or Firm* — Thomas | Horstemeyer, LLP(57) **CLAIM**

The ornamental design for a disc brake, as shown and described.

DESCRIPTION

FIG. 1 is a perspective view of our new disc brake; FIG. 2 is another perspective view of our new disc brake, from the same side as that of FIG. 1 and at a different angle; FIG. 3 is a side elevation view of our new disc brake of FIG. 1;

FIG. 4 is another side elevation view of our new disc brake of FIG. 1, the opposite side being a mirror image thereof; and,

FIG. 5 is a side elevation view of our new disc brake, from a side opposite that of FIG. 3.
